FURNACE

Howard J. Kerr, Westfield, N. J., assignor to The Babcock & Wilcox Company, Newark, N. J., a corporation of New Jersey

Application March 23, 1937, Serial No. 132,480

14 Claims. (Cl. 122—336)

The present invention relates in general to the construction and operation of furnaces for burning pulverized fuel in suspension, and more particularly to multi-stage furnaces of this type especially adapted for use in a steam boiler unit.

Pulverized fuel furnaces have heretofore been developed in which a stream of pulverized fuel and air for combustion is introduced into and burned in suspension in a furnace chamber in which a normal mean temperature above the fuel ash fusion temperature is maintained. Under such conditions the particles of incombustible fuel residue separating from the fuel and flame stream will be in a molten condition and tend to deposit as molten slag on the furnace bottom. The accumulating slag is continuously or intermittently removed in a molten condition through openings in the furnace bottom or side walls.

When a furnace chamber of the character described forms the primary or high temperature stage of a two-stage furnace, the second or low temperature furnace stage is substantially shielded from the radiant heat of the primary section by a separating baffle or partition below which the fuel and flame stream from the primary section passes through a screen formed by spaced water tubes. Combustion is completed in the second furnace section at a normal mean furnace temperature below the fuel ash fusion temperature so that the ash particles separating in that section will be mainly in a solid or "dry" condition. The ash separating in the second section is separately removed.

The main object of my invention is the provision of an improved construction and method of operation of a pulverized fuel burning furnace which is characterized by its capacity for use with fuels having a wide range of ash fusion temperatures while maintaining high heat release rates in the furnace, separation of a high percentage of the ash constituents in the furnace, and continuous removal of the separated ash or slag over a wide range of operating conditions. A further and more specific object is the provision of a pulverized fuel furnace of the two-stage type which is characterized by the removal of all the ash separating in the furnace through the portion of the furnace bottom below the second or low temperature section. A further object is the provision of a steam boiler unit with a water cooled furnace of the type described which is further characterized by a relative arrangement of the furnace chamber and boiler generating surface which shields the boiler generating tubes from the furnace radiant heat and

minimizes the deposition of slag on the boiler tubes.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described a preferred embodiment of my invention.

Of the drawings:

Fig. 1 is a sectional elevation taken on the line 1—1 of Fig. 2 illustrating a two-drum integral furnace type steam boiler constructed in accordance with my invention;

Fig. 2 is a horizontal section taken on the line 2—2 of Fig. 1;

Fig. 3 is a longitudinal vertical section taken on the line 3—3 of Fig. 2; and

Fig. 4 is an enlarged sectional view of a portion of the furnace slag screen taken on the line 4—4 of Fig. 3.

The steam boiler illustrated comprises an upper steam and water drum 10 and a parallel lower water drum 11 slightly offset therefrom and connected thereto by an inclined bank of vertically disposed steam generating tubes 12. The drums and tube bank are arranged along one side of a setting of rectangular horizontal cross-section formed by a vertically disposed front wall 13, rear wall 14, and side walls 15 and 16. The setting space laterally adjoining the tube bank is occupied by a pulverized fuel burning furnace.

Tubes 12^a of the innermost row of the tube bank are spaced from the remaining portion of the bank and provided with a multiplicity of projecting metallic studs for anchoring initially plastic refractory material which fills the inter-tube spaces and covers the furnace side of the tubes 12^a to define a refractory faced partition 17 extending from the front wall rearwardly along the tube bank and separating the tube bank for a major portion of its length from the furnace.

A row of substantially horizontal water tubes 18 extends laterally from the lower drum to a longitudinal header 19 at the base of the side wall 15, with the spaces between the tubes 18 being closed by suitable metallic tube blocks 20 to form a flat floor for the furnace chamber extending from the front wall to a point adjacent the rear end of the partition 17. A row of stud

tubes 21 extends upwardly along the side wall 15 and inclined across the arch 22 to the upper drum 10. The stud tubes along the forward portion of the side wall have refractory material 5 filling the intertube spaces and covering the furnace side of the tubes, while the tubes 21^a in the rear section are partly studded, with the refractory material only in the intertube spaces and a portion of the tube surface directly exposed 10 to the furnace chamber. A row of fully studded tubes 25 covered by refractory extends upwardly along the front wall 13 from a transverse header 26 connected to the lower drum. The upper ends 15 of the tubes 25 are connected to a similar transverse header (not shown) connected to the upper drum.

The arch sections of some of the tubes 21 have their studs and refractory omitted to define a fuel burner port 29 in the arch. Suitable pulverized fuel burners 30 discharge a multiplicity of thin streams of finely divided solid fuel and air for combustion downwardly through the inter-tube spaces into the furnace chamber. A row of stud tubes 31 similar to the tubes 21^a extends upwardly from a transverse header 32 along the rear wall 14 with their upper portions connected to an inclined header 33 leading to the upper drum.

The furnace chamber is thus defined by fluid cooled walls throughout its length, with the inner wall surface of the front section of the furnace chamber being mainly refractory-faced thus contributing to the maintenance of high temperatures in the front section, which in view of the fuel introduction into that section will be the zone of most active combustion, while the inner wall surface of the rear section contains a large amount of exposed metallic heat absorbing surface which facilitates the maintenance of a lower temperature in that section.

The tubes 12^b in the innermost row of the tube bank beyond the end of the partition 17 are spaced to provide a slag screen across the space between the end of the partition 17 and the rear wall 14, through which space the furnace chamber communicates with the space occupied by the tube bank. Most of the tubes 12^b extend downwardly below the drum 11 along the corresponding side of the ash pit hereinafter described and are connected to a longitudinally extending header 34, as shown in Fig. 1. A group of vertically disposed return bend superheater tubes 35 are arranged at the outer side of this portion of the tube bank. Transverse baffles 36 and 37 cooperate with the partition 17 and side wall 16 to provide a plurality of serially connected transverse gas passes across the tube bank leading to a stack connection at the front end of the same.

In accordance with my invention the front and rear sections of the furnace chamber are separated by a refractory covered screen 40 extending across the furnace chamber from the partition 17 to the side wall 15. The furnace screen 40 is formed by two staggered rows of vertically disposed stud tubes 41 with corresponding tubes in the two rows arranged in pairs and each tube covered by refractory material 42 held in position by studs 41a of different lengths on the tube periphery. The studs of greatest length on each tube extend toward the other tube of the pair and with the refractory covering form a built-up tube structure of generally ovate cross-section with its smaller end slightly separated from the corresponding end of the other tube. The major axis of each tube structure is arranged obliquely

to the plane of the tube row, so that adjacent pairs of tubes define gas flow passages 45 directed outwardly and rearwardly. The upper portions of the screen tubes 41 are bent outwardly and substantially parallel to the partition tubes 12^a. The passages between the upper bent portions of the screen tubes will be narrower than between the lower straight portions. This arrangement of the screen tubes and passages also provides an effective shield for the rear end of the main tube bank from radiant heat from the front section of the furnace chamber. The tubes 41 extend between a transverse lower header 43 and an inclined upper header 44 connected to the upper drum 10. A cooling fluid circulation is thus provided through the screen tubes. The cooling effect provided is such that in operation the exposed surface of the supported refractory material is at a temperature approaching the fuel ash fusion temperature.

As shown in Fig. 3, the furnace floor terminates a short distance rearwardly of the furnace screen and above the front end of a fluid cooled hopper 50 extending across the rear end of the furnace chamber. The rear wall of the hopper 50 is formed by a row of steeply inclined tubes 51 having their lower ends rounded and connected to a header 52 and their upper ends connected to the rear wall header 32. The tubes 51 are covered by metallic blocks 53 forming a smooth inclined fluid cooled floor leading to a transverse pit 54 from which the depositing material is removed in any suitable manner. The front wall of the hopper is similarly constructed and symmetrically arranged with respect to the rear wall, the front wall tubes 51^a extending between the slag screen header 43 and a parallel bottom header 56. The headers 52 and 56 are connected in any suitable manner to the lower drum 11 to provide a cooling fluid circulation through the hopper, rear wall and furnace screen tubes. Breaker blocks 57 at the nose of each hopper inclined wall facilitate the discharge of deposited material. The inner side wall of the hopper is cooled by the lower portions of the slag screen tubes 12^b. The rearmost partition tubes 12^a are also extended down along this wall to the header 34. Additional cooling tubes 58 extend from the lower drum to the header 34 along the extended partition tubes. Tubes 59 provide a water supply to the header 34 from the lower drum. The opposite vertical wall of the hopper is cooled by corresponding side wall tubes 21^a which are extended downwardly to a longitudinal header 60 connected to the lower drum.

In the operation of the steam boiler unit described, streams of pulverized coal surrounded by sufficient air for its combustion are downwardly discharged at the front end of the furnace chamber and the fuel ignited and burned in suspension in the front section. Due to formation of the parts defining the front section of the furnace chamber with a large percentage of exposed refractory area and the burning of the pulverized fuel at a high heat release rate, a high temperature may be easily maintained therein. A rate of heat absorption is maintained in these parts providing a normal mean temperature above the fuel ash fusion temperature so that the ash particles separating from the fuel stream in the front section of the furnace chamber will be received on the floor in a molten condition. The metallic floor blocks rapidly acquire a thin coating of this slag, and while the portion of the slag directly contacting with the floor blocks will ordinary 60 65 70 75

narily become chilled, additional slag deposits will remain in a molten condition. The presence of this layer of molten slag on the furnace chamber floor contributes to the maintenance of the desirable high furnace temperatures in the front section.

As the burning fuel streams pass rearwardly they contact with the furnace screen elements. The screen elements cause further mixing of the burning gases and air and insure the completion of combustion of the fuel in the rear section adjacent the furnace screen. Ash particles in suspension in the fuel stream contact with the refractory covering on the screen tubes and rapidly accumulate as slag thereon, providing sticky surfaces on which additional particles impinge and collect. The heat insulating characteristics of this refractory and the relatively low cooling effect of the screen tubes on the outer surface of the refractory causes the slag deposits to remain in a molten condition and continuously flow downwardly to the furnace floor. The molten slag accumulated in the front furnace chamber section and that collected by the screen tubes flows along the furnace floor through the passages 45 in the furnace screen to the rear edge of the furnace floor.

Only a small portion of the furnace floor extends beyond the furnace screen so that the molten slag passing through the furnace screen passages is not cooled to any substantial extent by the lower temperature conditions in the rear furnace section before reaching the rear edge of the floor. The described arrangement of the floor rear end contributes to the discharge therefrom of the molten slag in a multiplicity of small thin streams which rapidly break up into separate drops or globules falling onto the inclined front wall of the hopper. The slag globules are rapidly cooled while falling to and sliding or rolling down the hopper front wall, so that on reaching the pit 54 the globules will no longer be in a molten condition.

The heat absorbing surface in the rear section is arranged and proportioned to maintain a rate of heat absorption therein providing a normal mean temperature therein below the fuel ash fusion temperature, whereby ash particles separating therein will be or rapidly become chilled and deposit on the inclined hopper walls in a dry condition. The ash particles depositing on the inclined hopper floors roll or slide into the pit 54 from which they are removed with the slag descending from the rear edge of the floor.

The heating gases turn in the rear section of the furnace chamber around the rear end of the partition and enter the space occupied by the main tube bank. The heating gases initially pass across the boiler slag screen tubes, which cool the remaining ash particles in suspension. Slag collecting on the boiler slag screen tubes may fall or be blown off the tubes into the hopper 50. The gas stream then flows across the rear end of the tube bank and superheater tubes and forwardly through the transverse gas passes over the remaining portion of the tube bank.

The two-stage furnace construction described permits a highly effective use of radiant heat in efficiently and rapidly burning a slag-forming fuel and separating most of the ash constituents of the fuel before the heating gases leave the furnace. The radiant heat effect is almost wholly confined to the first or high temperature stage of the furnace chamber where combustion is initiated and most active and where the ash constituents tend to separate in a molten condition.

The tubes in the main bank and superheater accordingly will be shielded from radiant heat and slag deposits, thus reducing the cost of operation considerably. These results can be maintained with a wide range of fuels of varying ash characteristics and over a wide range of combustion rates.

While in accordance with the provisions of the statutes I have illustrated and described herein one form of my invention, those skilled in the art will understand that changes may be made in the form of the apparatus disclosed without departing from the spirit of the invention covered by claims, and that certain features of my invention may sometimes be used to advantage without a corresponding use of other features. In the claims the term "slag" is used to denote molten ash particles which have agglomerated or fused together on an arresting surface and which may be in either a molten or solid state.

I claim:

1. A furnace for burning finely divided solid fuel comprising walls defining a furnace chamber, means for introducing a stream of finely divided solid fuel and air for combustion into said furnace chamber, means forming a screen extending across said furnace chamber at a point spaced from the point of fuel introduction and having slag flow passages therein adjacent the floor level of the portion of said furnace chamber in front of said screen, said furnace chamber front portion having a closed floor therein constructed to support a layer of slag in a molten condition, and an ash receiving space below the portion of said furnace chamber at the rear of said screen constructed to receive slag flowing through said screen passages from said front furnace chamber portion.

2. A furnace for burning finely divided solid fuel comprising walls defining a furnace chamber, means for introducing a stream of finely divided solid fuel and air for combustion into said furnace chamber, means forming a fluid cooled screen extending across said furnace chamber at a point spaced from the point of fuel introduction and having slag flow passages therein adjacent the floor level of the portion of said furnace chamber in front of said screen, heat absorbing surface lining said furnace chamber front portion and constructed to maintain a normal mean temperature therein above the fuel ash fusion temperature including a closed fluid cooled floor therein constructed to support a layer of slag in a molten condition, and an ash receiving space below the portion of said furnace chamber at the rear of said screen and constructed to receive slag flowing through said screen passages from said front furnace chamber portion.

3. A furnace for burning finely divided solid fuel comprising vertically disposed walls defining a furnace chamber, means at the front end of said furnace chamber for introducing a stream of finely divided solid fuel and air for combustion, a group of vertically disposed refractory-covered tubes arranged to form a slag collecting screen extending across said furnace chamber at a point spaced from the point of fuel introduction and having slag flow passages therein adjacent the floor level of the portion of said furnace chamber in front of said slag screen, heat absorbing surface lining said furnace chamber front portion and constructed to maintain a normal mean temperature therein above the fuel ash fusion temperature including a closed fluid cooled floor therein constructed to support a layer

of slag in a molten condition, and a fluid cooled hopper in the rear portion of said furnace chamber and constructed to receive slag flowing through said screen passages from said front furnace chamber portion over the rear end of said floor.

4. A furnace for burning finely divided solid fuel comprising walls defining a furnace chamber, means for introducing a stream of finely divided solid fuel and air for combustion into said furnace chamber, means forming a slag collecting screen extending across said furnace chamber at a point spaced from the point of fuel introduction and having slag flow passages therein adjacent the floor level of the portion of said furnace chamber in front of said screen, heat absorbing surface lining said furnace chamber front portion and constructed to maintain a normal mean temperature therein above the fuel ash fusion temperature including a closed fluid cooled floor therein constructed to support a layer of slag in a molten condition, heat absorbing surface lining the rear portion of said furnace chamber and constructed to maintain a normal mean temperature therein below the fuel ash fusion temperature, and an ash receiving space in the rear portion of said furnace chamber constructed to receive ash separating in said rear portion and slag flowing through said screen passages from said front furnace chamber portion over the rear end of said floor.

5. A furnace for burning finely divided solid fuel comprising vertically disposed walls defining a furnace chamber, means at the front end of said furnace chamber for downwardly discharging a stream of finely divided solid fuel and air for combustion, a group of vertically disposed refractory-covered tubes arranged to form a slag collecting screen across said furnace chamber at a point spaced from the point of fuel introduction and having slag flow passages therein adjacent the floor level of the portion of the furnace chamber in front of said screen, heat absorbing surface lining said front portion and constructed to maintain a normal mean temperature therein above the fuel ash fusion temperature including a closed fluid cooled floor constructed to support a layer of slag in a molten condition and extending rearwardly of said screen, heat absorbing surface lining the rear portion of said furnace chamber and constructed to maintain a normal mean temperature therein below the fuel ash fusion temperature, and a fluid cooled hopper in the rear portion of said furnace chamber and constructed to receive dry ash separating in said rear portion and slag flowing through said slag screen passages over the rear end of said floor.

6. A steam generator comprising vertically disposed walls defining a furnace chamber having a heating gas outlet, means for introducing a stream of finely divided solid fuel and air for combustion into said furnace chamber, means forming a slag collecting screen across said furnace chamber at a point between the point of fuel introduction and said gas outlet and having slag flow passages therein adjacent the floor level of the portion of the furnace chamber in front of said slag screen, heat absorbing surface lining the portion of said furnace chamber in front of said slag screen and constructed to maintain a normal mean temperature therein above the fuel ash fusion temperature including a fluid cooled floor constructed to support a layer of slag in a molten condition, heat absorbing surface lining the rear portion of said furnace chamber

and constructed to maintain a normal mean temperature therein below the fuel ash fusion temperature, a hopper in the rear portion of said furnace chamber and constructed to receive ash separating in said rear portion and slag flowing through said screen passages over the rear end of said floor, means defining a heating gas pass connected to said gas outlet, and steam generating surface arranged in said gas pass so as to minimize radiant heat absorption from said front section.

7. A steam generator comprising a pair of upper and lower horizontally arranged drums, a bank of vertically disposed steam generating tubes extending between and connected to said drums, means defining a furnace chamber laterally adjoining the space containing said tube bank and communicating therewith adjacent its rear end, means at the front end of said furnace chamber for introducing a stream of finely divided solid fuel and air for combustion, means forming a screen extending across said furnace chamber at a point spaced from the point of fuel introduction and having slag flow passages therein adjacent the floor level of the portion of said furnace chamber in front of said screen, a fluid cooled floor for said front portion constructed to support a layer of slag in a molten condition, and a hopper at the rear of said slag screen constructed to receive ash separating in said rear portion and slag flowing through said screen passages.

8. A steam generator comprising a pair of upper and lower horizontally arranged drums, a bank of vertically disposed steam generating tubes extending between and connected to said drums, means defining a furnace chamber laterally adjoining the space containing said tube bank and communicating therewith adjacent its rear end, means at the front end of said furnace chamber for introducing a stream of finely divided solid fuel and air for combustion, a group of vertically disposed refractory-covered tubes arranged to form a slag collecting screen extending across said furnace chamber at a point spaced from the point of fuel introduction and having slag flow passages therein adjacent the floor level of the portion of said furnace chamber in front of said slag screen, heat absorbing surface lining said furnace chamber front portion and constructed to maintain a normal mean temperature therein above the fuel ash fusion temperature including a fluid cooled floor constructed to support a layer of slag in a molten condition, heat absorbing surface lining the rear portion of said furnace chamber and constructed to maintain a normal mean temperature therein below the fuel ash fusion temperature, and a fluid cooled hopper in the rear portion of said furnace chamber constructed to receive ash separating in said rear portion and slag flowing through said screen passages over the rear end of said floor.

9. In a furnace having a two-stage furnace chamber divided into communicating front and rear sections separated by a fluid cooled screen, the method of burning a finely divided solid fuel and separating ash constituents of the fuel in the furnace which comprises introducing a stream of the fuel and air for combustion into the front section of the furnace chamber and burning the fuel in suspension therein at a relatively high rate of heat release, collecting and maintaining a layer of slag in a molten condition on the portion of the furnace bottom below said front section, directing the burning fuel stream through

said screen into said rear section, and causing the slag in said front section to pass through said screen into said rear section.

10. In a furnace having a two-stage furnace chamber divided into communicating front and rear sections separated by a refractory covered screen, the method of burning a finely divided solid fuel and separating ash constituents of the fuel in the furnace which comprises introducing a stream of the fuel and air for combustion into the front section of the furnace chamber and burning the fuel in suspension therein at a relatively high rate of heat release, maintaining a rate of heat absorption in said front section providing a normal mean temperature therein above the fuel ash fusion temperature, whereby ash particles separated therein will be in a molten condition, collecting and maintaining a layer of molten slag on the portion of the furnace bottom 20 below said front section, directing the burning fuel stream through said refractory-covered screen to effect the removal of ash particles in suspension, and causing the slag formed in said front section to pass through said screen into the portion of the furnace bottom below said rear section.

11. In a furnace having a two-stage furnace chamber divided into communicating front and rear sections separated by a refractory-covered screen, the method of burning a finely divided solid fuel and separating ash constituents of the fuel in the furnace which comprises introducing a stream of the fuel and air for combustion into the front section of the furnace chamber and burning the fuel in suspension therein at a relatively high rate of heat release, maintaining a rate of heat absorption in said front section providing a normal mean temperature therein above the fuel ash fusion temperature, maintaining a rate 40 of heat absorption in said rear section providing a normal mean temperature therein below the fuel ash fusion temperature, whereby ash separating therein will be in a dry condition, directing the burning fuel stream through said screen to effect the removal of ash particles in suspension in a molten condition, and collecting the ash separating in said rear section and the slag collected by said screen in the portion of the furnace bottom at the rear of said screen.

50. 12. In a furnace having a two-stage furnace chamber divided into communicating front and rear sections separated by a refractory-covered screen, the method of burning a finely divided solid fuel and recovering ash constituents of the fuel in the furnace which comprises downwardly discharging a stream of the fuel and air for combustion into the front section of the furnace chamber and burning the fuel in suspension therein at a relatively high rate of heat release, maintaining a rate of heat absorption in said front section providing a normal mean temperature therein above the fuel ash fusion temperature, whereby ash particles separating therein will be in a molten condition, collecting and maintaining a layer of molten slag on the portion of the furnace bottom below said front section, main-

taining a rate of heat absorption in said rear section providing a normal mean temperature therein below the fuel ash fusion temperature, whereby ash separating therein will be in a dry condition, directing the burning fuel stream through said screen to effect the removal of ash particles in suspension in a molten condition, and collecting the slag and ash separating in said front and rear sections and the slag collected by said screen in the portion of the furnace bottom at the rear of said screen. 10

13. A furnace for burning a finely divided solid fuel comprising walls defining a furnace chamber, means arranged to divide said furnace chamber into a front high temperature section and a rear low temperature section, said sections communicating at their lower portions, means for introducing a stream of finely divided solid fuel and combustion air into said high temperature section and burning the fuel in suspension therein, heat absorbing surface lining said high temperature section and constructed to maintain a normal mean temperature therein above the fuel ash fusion temperature, a closed fluid cooled floor forming the bottom of said high temperature section and constructed to support separated slag depositing thereon in a molten condition and discharge the same over its rear end, heat absorbing surface lining said low temperature section and constructed to maintain a normal mean temperature therein below the fuel ash fusion temperature, and a hopper at the bottom of said low temperature section extending below the level of said floor and arranged to receive ash separating in said low temperature section and slag flowing over the rear end of said floor. 15 20 25 30 35

14. A furnace for burning a finely divided solid fuel comprising walls defining a furnace chamber, means including a vertically disposed row of water tubes arranged to divide said furnace chamber into a front high temperature section and a rear low temperature section, said sections communicating at their lower portions, means for introducing a stream of finely divided solid fuel and combustion air into said high temperature section and burning the fuel in suspension at a relatively high rate of heat release while traveling therein, heat absorbing surface lining said high temperature section and constructed to maintain a normal mean temperature therein above the fuel ash fusion temperature, a substantially horizontal closed fluid cooled floor forming the bottom of said high temperature section and constructed to support a layer of slag depositing thereon in a molten condition and discharge the same over its rear end, heat absorbing surface lining said low temperature section and constructed to maintain a normal mean temperature therein below the fuel ash fusion temperature, and a fluid cooled ash hopper at the bottom of said low temperature section extending below the level of said floor and arranged to receive ash separating in said low temperature section and slag flowing over the rear end of said floor. 40 45 50 55 60 65

HOWARD J. KERR.
